UNITED STATES PATENT OFFICE.

FRIEDRICH JULIUS ROBERT WAGNER, OF BERLIN, GERMANY, ASSIGNOR,
BY MESNE ASSIGNMENTS, TO GENERAL ELECTRIC COMPANY, A COR-
PORATION OF NEW YORK.

AUTOMATIC AIR-BRAKE.

No. 823,979.

Specification of Letters Patent.

Patented June 19, 1906.

Application filed December 9, 1899. Serial No. 739,792.

To all whom it may concern:

Be it known that I, FRIEDRICH JULIUS ROBERT WAGNER, a subject of the German Emperor, residing at Berlin, in the Empire of Germany, have invented a certain new and useful Improvement in Automatic Air-Brakes, (Case No. 273,) of which the following is a full, clear, concise, and exact description, reference being had to the accompanying drawings, forming a part of this specification.

For the accomplishment of simultaneous operation of all the brake-cylinders in the automatic air-brakes several schemes have been devised. The present invention provides a means whereby through the simultaneous operation of all the triple valves in the air-brake system compressed air is fed to the brake-cylinders, and independently of the triple valve the pressure in the braking cylinders is reduced, in connection with the present braking apparatus employed. The energy which is released when a change of pressure occurs in the train-pipe through which the triple valves are operated is utilized for braking. This is accomplished by the use of electrically-operated by-passes which are placed between the train-pipe and the brake-cylinder. These are so constructed that according to their position the braking-cylinder is connected either with the train-pipe or with the atmosphere or closed to both of these sources. These electrically-operated valves, which of themselves do not constitute the subject-matter of this patent, may be constructed in several different ways and operated in a number of ways. The electrically-operated valves may be replaced by other similar equivalent means whose adaptation will be apparent to those skilled in the art. Whichever construction is used they are connected with the stand near the driving-locomotive by means of electric circuits and are simultaneously operated by the engineer. The controller used to operate these valves is mechanically united with the engineer's valve for the air-brake in such manner that during the electric operation of the air-brake the train-pipe is disconnected from the air-reservoir on the locomotive just as it is disconnected from the air-reservoir by the pneumatic operation of the brake, so that the feeding of the train-pipe cannot take place.

If the electrically-operated valves connect the brake-cylinder with the train-pipe, then a simultaneous decrease of pressure in this train-pipe will take place, which operates on the triple valve, thereby simultaneously operating all the brakes. If the electrically-operated valves unite the braking-cylinder with the air, then all the brakes are more or less released, according to the length of time of this connection.

In the drawings, Figure 1 is a view, partly in elevation and partly in section, of an air-brake system embodying my invention. Figs. 2 to 7, inclusive, are views of a portion of the apparatus, sufficient to show the operation thereof, partly in vertical section and partly in diagram in different operating positions.

The accompanying drawings show the application of the invention to the Westinghouse quick-braking system by the use of electrically-operated valves which are operated by solenoids.

The braking-cylinder 1, Fig. 1, the auxiliary reservoir 2, the triple valve 3, and the train-pipe 4 are shown in their ordinary present structure and combination. Braking-cylinder and train-pipe are united through the pipe 5, in which the electric valves 6 and 7 are placed through passage 8 and nipple 9. The pipe 5 is connected on one side to the cover 10 of the triple valve 3, and on the other side to the braking-cylinder 1 by means of a neck 11. The changes to the present triple valve which are occasioned hereby are easily made. The valves 6 and 7 are held to their seats by means of the springs 12 and 13. Valve 6 closes the brake-cylinder from the train-pipe, and valve 7 disunites the brake-cylinder from the atmosphere. To the valve 6 and 7 armatures 18 and 19 are united, which project into the solenoids 14 and 15, these being united on one side to the conductors 16 and 17, respectively, their other terminals being connected to conductor 20. In place of the third conductor 20 the earth may be used. The valves are raised when the controller-handle on the locomotive directs current into either the conductors 16 or 17. If current is conducted through the wire 16, then valve 6 is raised and the brake-cylinder is filled with compressed air from the train-pipe 4. If current passes through wire 17, then valve 7 is raised and the braking-cylinder is emptied.

into the atmosphere through the atmospheric exhaust 41.

The controlling apparatus is for simplicity's sake shown as applied to the Westinghouse engineer's valve; but it is not necessary that this form be used, as the controlling device may be attached to any of the present forms of engineers' valves used. The handle of the engineer's valve, Fig. 3, consists of two parts, of which part 21 is secured to plate 22, while part 23 is secured to part 21, but revolvable about the projection 24, it being lifted from the contact-bars by means of spring 25. At the end of the lever 23 a current-contact 10 piece 26 is mounted. On the top of the engineer's valve the contact-rings 27, 28, and 29 are mounted and insulated from each other. Of these contact-pieces 27 is united with conductor 17, 28 with conductor 16, and 29 with the positive pole of the accumulator-battery 30. The negative pole of the battery 30 is connected to the common return-wire 20.

The opposite ends of the contact-bars 27 and 28, as also both ends of the contact-bar 29, may be preferably inclined so that the contact-piece 26 just touches the raised portions of these bars in three positions *a*, *b*, and *c*, Figs. 2, 6, and 7, it not being necessary in these positions for the operator to press it down. In the intermediate positions, Figs. 3, 4, 5, the contact-bar 29 is united with contact-bar 27 or 28 through the contact-piece 26 only when the latter is pressed down by hand. The compressed air which flows from the main reservoir through the pipe 31 passes either through the opening 32 or the opening 33 and the pressure-reducing valve 34 into the train-pipe 4. When the train-pipe is filled with compressed air, then a chamber 36, which is united with the usual small reservoir 37, is also supplied with air at the same pressure as that in the train-pipe by means of the passage 35. The chamber 36 is disconnected from the train-pipe 4 through the piston 38, which is united with the valve 39. This valve 39 disconnects in its lowest position the train-pipe 4 from the atmosphere. Figs. 2 to 7 show the controlling arrangement 45 in its different positions. In the position of Fig. 2 (simultaneous, pneumatic, and electric brake releases) the train-pipe 4 is fed from the main air-reservoir by means of the passage 32. Then the braking-cylinders simultaneously discharge through the triple valves on account of the increase of pressure in the pipes in a well-known way. At the same time this discharge is also accomplished through valve 7 and, moreover, automatically, inasmuch as the contact-bars 27 and 28 are raised in this position, so that they are short-circuited by the contact-piece 26, it not being necessary for the operator to press the contact-piece 26 down in this position. The 60 release of the brakes is thereby accomplished

pneumatically as well as electrically, it not being necessary to use the special handle for this double operation. In the position of Fig. 3 (running position) the train-pipe is united with the air-reservoir in a well-known way by means of the pressure-reducing valve 34. In the two positions of Figs. 4 and 5 (electric brake-release and electric braking) the train-pipe is totally disunited from the main air-reservoir and from the external air, a braking or a brake release, by pneumatic means not being possible. In the position of Fig. 5 the valve 6 may be opened by pressing down the contact-lever 23, whereby a simultaneous operation of the triple valves in the whole train effects a braking of all the cars in the system supplied with brakes. After revolving the handle into position (shown in Fig. 4) the valve 7 may be operated by pressing down the contact-lever 23, whereby the braking-cylinders are opened to the atmosphere, any desired release of the brakes being thereby accomplished. In the position of Fig. 6 (simultaneous, pneumatic, and electric braking) the train-pipe is united with the air through the valve 39. In the position of Fig. 7 (simultaneous, pneumatic, and electric emergency braking) the train-pipe is united with the atmosphere in the engineer's valve. By relieving the pressure in the train-pipe the brakes are applied, respectively, for the respective service-stop and emergency-stop in a well-known way. In the last two positions the valves 6 are always opened, whereby all the triple valves are simultaneously operated.

Due to the above-mentioned inclination of the contact-bars 28 and 29 the circuit is completed through the contact-piece automatically, so that the simultaneous, pneumatic, and electric operation of the triple valves without the extra handle, excepting the one usually used in the engineer's valve, is effected. To guard against the escape of compressed air from brake-cylinders through the valve 6 into the atmosphere in the position indicated in Figs. 6 and 7, it is well to employ between the triple valves and the electric valves a check-valve 40.

Having thus described one embodiment of my invention, I claim as new, and desire to secure by Letters Patent, the following:

1. In an air-brake system, the combination with a brake-cylinder, a train-pipe, a pneumatically-actuated valve responsive to variations of pressure in the train-pipe and adapted to control the pressure in the brake-cylinder, a manually-operated valve for controlling the train-pipe pressure, electrically controlled means for connecting the brake-cylinder to train-line or to atmosphere independently of said pneumatically-actuated valve, and switching mechanism for controlling said means.
2. In an "automatic" air-brake system, in

combination with the train-pipe, engineer's valve, triple valve, and brake-cylinder, electrically - controlled means for connecting brake-cylinder to train-line or to atmosphere independently of the triple valve, and switching mechanism associated with the motor-man's valve for controlling said means.

3. In an air-brake system, the combination with a brake-cylinder and a train-pipe, of a pneumatic valve interposed between said train-pipe and said brake-cylinder to cause the operation of the piston therein, a source of fluid under pressure, an engineer's valve interposed between said source and said train-pipe whereby said engineer's valve is adapted to effect the operation of the pneumatic valve, electric valve mechanism associated with the brake-cylinder and the train-pipe, said electric valve mechanism being adapted to effect the actuation of the pneumatic valve, switch mechanism for controlling the electric valve mechanism, and means whereby said electric valve mechanism is adapted to control the flow of fluid into and out of the said braking-cylinder when the train-pipe is disconnected from the source of supply by the aforesaid engineer's valve, substantially as described.

4. In combination, a brake-cylinder, a triple valve, a train-pipe, an engineer's valve, electromagnetic valve mechanism adapted to connect the brake-cylinder either with the train-pipe or the atmosphere, means for controlling the operation of said electromagnetic valve mechanism, and means whereby said electromagnetic valve mechanism is adapted to effect the operation of the triple valve whereby to apply the brakes, substantially as described.

5. In combination, a brake-cylinder, a triple valve, a train-pipe, an engineer's valve, a source of fluid-supply, electromagnetic valve mechanism adapted to effect the operation of the triple valve, a switch-handle associated with the engineer's valve for controlling the electromagnetic valve mechanism, and means associated with said engineer's valve whereby the electromagnetic valve mechanism is adapted to connect brake-cylinder to the train-pipe or to atmosphere independently of said triple valve when the train-pipe is disconnected from the source of fluid-supply, substantially as described.

6. The combination with a brake-cylinder, of a source of fluid-supply for actuating the piston therein, electric valve mechanism for controlling the flow of fluid into said cylinder and exhausting the same therefrom, said valve mechanism comprising two valves, a valve-chamber associated with each valve, two additional chambers, one in association with each valve, each valve being adapted to effect communication between its valve-chamber and one of said additional chambers, a communicating duct leading from the

valve-chamber of one valve to the additional chamber of the other valve, and electric means for operating said valves, substantially as described.

7. In an air-brake system, the combination with a brake-cylinder, of a source of fluid-supply, electric valve mechanism disposed between said fluid-supply and said brake-cylinder for controlling the operation of the piston therein, a rotatably-mounted switch-handle for actuating said valve mechanism, contact-bars adapted to be electrically interconnected by said handle, said handle being pivotally mounted upon its rotatable support, and means whereby said handle is adapted to close circuit through said contact-bars in some angular positions without being pivotally actuated, substantially as described.

8. An air-brake system comprising pneumatic and electric controlling means each operative independently both to apply and to release the brakes, and means whereby the electric controlling means can control the pneumatic controlling means.

9. An air-brake system comprising two different sets of controlling means each operative independently both to apply and to release the brakes, and connections whereby one of said controlling means can cause the operation of the other.

10. An air-brake system comprising a series of braking devices on different cars, pneumatic and electric controlling means by which said braking devices can be controlled from the engine either pneumatically or electrically both to apply and to release the brakes, and connections whereby the pneumatic controlling means can be effected at the different cars by the electric controlling means.

11. In an air-brake system, a manually-operated valve controlling the brakes, a handle therefor, a contact movably connected to said handle, a contact-strip adjacent to said handle and adapted to be engaged by the removable contact, said contact-strip having portions depressed out of the path of movement of the movable contact and other portions lying in said path, and electrically-operated brake-controlling means connected in circuit with said contacts.

12. In an air-brake system, a manually-operated valve controlling the brakes, a handle therefor, a contact yieldingly and movably connected to said handle, a contact-strip secured adjacent to said handle and adapted to be engaged by the movable contact, said contact-strip having raised and depressed portions, the raised portions lying in the normal path of movement of said movable contact and the depressed portions out of said path, means for moving the movable contact out of its normal path into contact with the depressed portions of said fixed contact, and

electrically - operated brake - controlling means connected in circuit with said contacts.

13. In an air-brake system, a manually-operated valve controlling the brakes, a handle therefor, a lever pivoted to said handle, a contact secured to said lever, contact-strips secured to the valve-casing and adapted to be electrically connected by the lever-contact, 10 said strips having raised and depressed portions, the raised portions lying in the normal path of movement of the lever-contact and the depressed portions out of said path, a spring for holding said lever-contact in its normal

path for engagement with the raised portions 15 of said strips and allowing it to be moved into engagement with the depressed portions; and electrically - operated brake - controlling means connected in circuit with said contact.

In witness whereof I hereunto subscribe my name this 15th day of November, A. D. 1899.

FRIEDRICH JULIUS ROBERT WAGNER.
